(57) **CLAIM**

The ornamental design for a high performance knee brace, as shown and described.

DESCRIPTION

FIG. 1 is a perspective view of high performance knee brace, showing our new design with the insert shown in perspective view and the pouch for the insert shown from the front; FIG. 2 is a front view of the pouch thereof, as seen from the inside of the knee brace;

FIG. 3 is a front elevational view;

FIG. 4 is a back elevational view;

FIG. 5 is a side elevational view;

FIG. 6 is a bottom plan view; and,

FIG. 7 is a top plan view.

The broken line showing in FIG. 1 is for illustrative purposes only and forms no part of the claimed design.
